United States Patent Office.

JOHN JOSEPH CHARLES SMITH, OF SOMERVILLE, ASSIGNOR TO THE METALLIC COMPRESSION-CASTING COMPANY, OF BOSTON, MASSACHUSETTS.

Letters Patent No. 99,020, dated January 18, 1870.

IMPROVEMENT IN BELL-PULLS.

The Schedule referred to in these Letters Patent and making part of the same.

I, JOHN JOSEPH CHARLES SMITH, of Somerville, in the county of Middlesex, and State of Massachusetts, have invented a new and improved Bell-Pull, which is described as follows:

Nature and Objects of the Invention.

My invention is intended primarily, though not exclusively, for outside door-bells; and consists, essentially, of a cylindrical hub, having a partial rotation in a plane perpendicular to the wall or other surface to which the bell-pull is applied, and operated by a knob, projecting from the hub in a direction coincident with the plane of its rotation, the said hub being constructed with concentric segmental flanges, which project from one end or face-plate of the hub, in such a manner as to adapt the whole for casting. Of these segmental flanges, one serves for the attachment of the bell-wire or chain, and a helical spring, which retracts the knob when released; and the other to mask or close the recess in which the hub works, all as hereinafter described.

General Description with Reference to the Drawing.

In the accompanying drawing—

Figure 1 represents a sectional elevation of my improved bell-pull in position, the section of the hub, &c., being taken in the plane indicated by the line *y y*, fig. 2.

Figure 2 represents a horizontal section of the same, in the plane indicated by the line *x x*, fig. 1.

Similar letters of reference indicate corresponding parts in both views.

From a plate, A, projects a pair of cheeks or lugs,

B, forming the bearings or attachments of an arbor, C, upon which the hub D turns.

The handle E, for turning the hub, rises obliquely from it, and terminates in a knob, F, projecting horizontally.

The bell-chain G is attached to a stud, h, upon a segmental flange, H, at the other end of the helical spring I, whose inner end is attached to the arbor C, so as to restore the parts to their normal position, represented in fig. 1, when the knob is released.

The outer concentric flange J serves to mask or cover the recess in which the hub works, and all the various parts of the rotating hub, with its handle E F, are so constructed and arranged that they may be readily cast in one piece, by means of my compressor-process, described in Letters Patent heretofore granted.

The handle projects in such a position, that a person desiring to pull the bell, whether familiar with the construction of the device or not, in drawing the knob outward from the wall, will also bear downward, so that a child, or other person with little strength, can, with great ease, apply all needful force to ring the bell.

I claim, as my invention—

The hub D, constructed with the concentric segmental flanges H J, handle E, and knob F, and employed in connection with the arbor C and helical spring I, all applied and arranged as and for the purposes set forth.

JOHN JOSEPH CHAS. SMITH.
